(57) **CLAIM**

What is claimed is, the ornamental design for a container with spiral shaped interior, as shown and described.

DESCRIPTION

FIG. 1 illustrates a top perspective view of the present invention.

FIG. 2 illustrates a front perspective view of the present invention.

FIG. 3 illustrates a rear perspective view of the present invention.

FIG. 4 illustrates a right side elevation view of the present invention.

FIG. 5 illustrates a left side elevation view of the present invention.

FIG. 6 illustrates a top plan view of the present invention; and,

FIG. 7 illustrates a bottom plan view of the present invention. The broken lines represent portions of the structure that form no part of the claim.
